CLAIM

The ornamental design for an inflatable float, as shown and described.

DESCRIPTION

FIG. 1 is a perspective view of the inflatable float showing the claimed design;

FIG. 2 is a left-side view of the inflatable float as shown in FIG. 1;

FIG. 3 is a right-side view of the inflatable float as shown in FIG. 1;

FIG. 4 is a front view of the inflatable float as shown in FIG. 1;

FIG. 5 is a back view of the inflatable float as shown in FIG. 1;

FIG. 6 is a top view of the inflatable float as shown in FIG. 1; and,

FIG. 7 is a bottom view of the inflatable float as shown in FIG. 1.

The broken lines in the figures show portions of the inflatable float that form no part of the claimed design.

1 Claim, 7 Drawing Sheets
